HANDLE FOR ELECTRIC SOLDERING IRON

Lawrence Emmerson House II, Baltimore, Md., assignor
to The Black & Decker Manufacturing Company,
Towson, Md.

Filed Jan. 30, 1974, Ser. No. 438,170

Term of patent 14 years

Int. Cl. D8—05

U.S. Cl. D8—30

FIG. 2

FIG. 3

FIG. 4

FIG. 5

FIG. 6

FIG. 1 is a perspective view of a handle for electric soldering iron incorporating my novel design.

FIG. 2 is a top plan view thereof on an enlarged scale.

FIG. 3 is a side elevational view thereof on an enlarged scale.

FIG. 4 is a bottom plan view thereof on an enlarged scale.

FIG. 5 is a front elevational view thereof on an enlarged scale.

FIG. 6 is a rear elevational view thereof on an enlarged scale.

The tip is shown in broken lines in FIGS. 1, 2, 3, 4, and 5 for illustrative purposes only.

I claim:

The ornamental design for a handle for electric soldering iron, as shown and described.
